(57) **CLAIM**

The ornamental design for a tool holder portion of an impact driver, as shown and described.

DESCRIPTION

FIG. 1 is a perspective view of a tool holder portion of an impact driver showing our new design;

FIG. 2 is right side elevational view showing the design for the tool holder portion of the impact driver of FIG. 1;

FIG. 3 is a left side elevational view showing the design for the tool holder portion of the impact driver of FIG. 1;

FIG. 4 is a front elevational view showing the design for the tool holder portion of the impact driver of FIG. 1;

FIG. 5 is a rear elevational view showing the design for the tool holder portion of the impact driver of FIG. 1;

FIG. 6 is a top plan view showing the design for the tool holder portion of the impact driver of FIG. 1; and,

FIG. 7 is a bottom plan view showing the design for the tool holder portion of the impact driver of FIG. 1.

The broken lines shown in the drawings illustrate portions of the impact driver that form no part of the claimed design.

1 Claim, 7 Drawing Sheets
